UNITED STATES PATENT OFFICE.

FRANK L. MORSE, OF ITHACA, NEW YORK.

LAWN-SPRINKLER.

1,307,634.

Specification of Letters Patent. Patented June 24, 1919.

Application filed November 9, 1916. Serial No. 130,308.

To all whom it may concern:

Be it known that I, FRANK L. MORSE, a citizen of the United States, residing at Ithaca, in the county of Tompkins and State 5 of New York, have invented a certain new and useful Improvement in Lawn-Sprinklers, of which improvement the following is a specification.

This invention relates to that class of lawn 10 sprinklers having radially extending nozzles mounted to rotate and discharge a stream of water throughout a circular area, and the main object is to provide improved means for varying the radial distance to 15 which the water will be thrown, as the arms or nozzles continue to revolve, whereby the water may be uniformly spread over substantially the full circular area.

In the accompanying drawings: Figure 1 20 is a vertical section of one form of sprinkler embodying my improvement; Fig. 2, a vertical section of the upper portion of a sprinkler showing a modification; Fig. 3, a horizontal section taken through one of the nozzles of the form of construction shown in 25 Fig. 2; Fig. 4, a vertical section, similar to Fig. 2, but showing another form of nozzles; and Fig. 5, a similar vertical section showing still another modification in which the 30 radial distance is controlled by moving a valve for varying the pressure with which the water is admitted to the revolving nozzles.

My improvement is designed to be employed in connection with sprinklers in 35 which the water is discharged from a revolving nozzle, and various means may be used for automatically varying the radial distance to which the water is discharged during the successive revolutions of the nozzle or nozzles.

According to the construction shown in 40 Fig. 1, the sprinkler comprises a body portion or casing, 6, having a supporting flange, 7, adapted to rest upon the ground, and containing a chamber, 8, and a vertical hollow cylindrical portion, 9, in which is rotatably mounted the bushing, 10, having the curved or helical blades or vanes, 11, and the hol-

low head, 12, rotatable therewith and carrying the hollow radial arms or nozzles, 13. The head, 12, is formed with a bushing having a shoulder, 14, fitted against a corresponding shoulder within the vertical cylindrical portion, 9, and thereby holding the 55 parts in position.

The chamber, 8, is adapted to be connected to the usual hose at the threaded opening, 15, and the force of the water flowing up through the bushing between the 60 curved blades, 11, serves to impart rotation to the bushing, 10, the head, 12, and the nozzles, 13. The nozzles may be inclined upward at a certain angle, and the water may be discharged through the openings, 16, 65 at the ends of the nozzles.

For the purpose of automatically varying the radial distance to which the water is discharged as the nozzles are rotated, I have shown in Fig. 1, movable deflector plates, 70 17, mounted on bent levers, 18, over the discharge openings, and connected at their inner ends to a vertical stem, 19, passing down through the axis of the revolving head, and into the chamber, 8, where it may be provided with a head, 20, bearing against a cam, 21. For driving the cam, I have shown a gear, 22, mounted axially on the lower end 75 of the revolving bushing, 10, and meshing with gear, 23, mounted on a vertical shaft 80 within a frame, 24, and carrying a worm gear, 25, at the lower end meshing with a gear, 26, on the cam shaft, 27, also mounted in the frame, 24, and carrying the cam, 21. The gear 26 is indicated in the conventional manner with teeth shown at one portion, only, but it will, of course, be understood that the teeth are to extend all the way around the circumference.

As the bushing is rotated by the force of 90 the water, the motion is transmitted through the gears, 22, 23, 25, and 26, to rotate the shaft 27, and the cam, 21, thereby imparting a vertical reciprocating movement to the stem, 19. This operates the bent levers, 95 18, to alternately raise and lower the deflectors, 17, over the nozzle openings from the position shown in full lines to that indicated

in dotted lines, whereby the issuing stream of water is thrown through the entire radial distance to the outer circumference of the circular area when the nozzle is unobstructed, and from this point is deflected gradually down to the base of the sprinkler at the center of said area, as the deflector reaches the position indicated in full lines. A spring, 28, may be employed to assist the movement of the rod, 19, in one direction, and keep the head, 20, in contact with the surface of the cam, 21. This cam may have any suitable curve or contour to produce the desired movement of the deflectors.

15 Another form of means for varying the radial distance to which the water is discharged during the revolutions of the nozzles, is shown in Figs. 2 and 3, in which, in lieu of the movable deflectors, the nozzles 20 themselves are mounted in hollow swivel joints, 30, in the head, 12, and are adapted to swing vertically by means of the reciprocating stem, 19. For this purpose the stem is provided with rack teeth, 31, at the upper end, which mesh with the segmental gears, 32, rigidly connected with the respective nozzles, and mounted to oscillate upon the respective axes of said swivel joints. In this way, the reciprocating movement of the stem, 19, operates to swing the nozzles gradually upward and downward between the position shown in full lines and that indicated in dotted lines in Fig. 2.

In the modification shown in Fig. 4, the 35 construction is substantially the same as that of Figs. 2 and 3, except that the nozzles, 13^a, are of a different form, having a hollow cylindrical base portion, 30^a, fitted within a corresponding socket in the head, 12^a. The 40 operation is the same as that shown in Figs. 2 and 3, and will be readily understood.

In Fig. 5, the nozzles, 13, are fixed at a certain angle of elevation, the same as in Fig. 1, and the variation in the radial distance of discharge is obtained by the regulating valve, 33, which is actuated by the stem, 19, and is alternately raised and lowered toward and from its seat, thereby varying the force of the stream discharged 50 through the nozzle or nozzles, and consequently gradually varying the radial discharge distance as the nozzles revolve.

Thus it will be seen that in all of the 55 modifications shown, a stream of water is discharged from each nozzle during the successive revolutions of the same, and that the radial distance to which the water is thrown is automatically and gradually varied from the outer circumference of the 60 circular area inward to the center, then outward to the circumference again, and so on, continuously until the entire circular area is thoroughly sprinkled.

Having now described my invention,

what I claim as new and desire to secure by Letters Patent is:

1. In a lawn sprinkler, the combination of a rotatable head having one or more nozzles with a discharge opening, means operated by the flow of the water for revolving said head, a reciprocatory stem located in the axis of said revolving head, driving mechanism operated by the flow of the water for reciprocating said stem, and means actuated by said stem for gradually varying the radial distance of discharge. 75

2. In a lawn sprinkler, the combination of a rotatable head having one or more nozzles with a discharge opening, means operated by the flow of the water for revolving 80 said head, a reciprocatory stem located in the axis of said revolving head, cam mechanism driven by the flow of the water for reciprocating said stem, and means actuated by said stem for gradually varying the 85 radial distance of discharge.

3. In a lawn sprinkler, the combination of a rotatable head having one or more nozzles with a discharge opening, means operated by the flow of the water for revolving 90 said head, a reciprocatory stem located in the axis of said revolving head, a cam for actuating said stem, gearing driven by the flow of water for driving the cam, and means actuated by the stem for gradually 95 varying the radial distance of discharge.

4. In a lawn sprinkler, the combination of a rotatable head having one or more nozzles with a discharge opening, means operated by the flow of the water for revolving 100 said head, a movable deflector for the discharge opening of each nozzle, and mechanism for positively and periodically moving said deflector over said discharge opening 105 to vary the radial distance of discharge.

5. In a lawn sprinkler, the combination of a rotatable head having one or more nozzles with a discharge opening, means operated by the flow of the water for revolving said head, a movable deflector for the discharge opening of each nozzle, and means 110 operated by the flow of the water for gradually moving said deflector back and forth over said discharge opening to vary the radial distance of discharge. 115

6. In a lawn sprinkler, the combination of a rotatable head having one or more nozzles with a discharge opening, means operated by the flow of the water for revolving said head, a reciprocatory member, mechanism operated by the flow of water for reciprocating said member, and a movable deflector for the discharge opening actuated by said reciprocating member. 120

7. In a lawn sprinkler, the combination of a rotatable head having one or more nozzles with a discharge opening, means operated by the flow of the water for revolving 125

said head, a reciprocatory stem located in the axis of said revolving head, driving mechanism for said stem, and a movable deflector for the discharge opening actuated by said stem.

8. In a lawn sprinkler, the combination of a rotatable head having one or more nozzles with a discharge opening, means oper-

ated by the flow of the water for revolving said head, a reciprocatory stem located in the axis of said revolving head, driving mechanism for said stem, a movable deflector for the discharge opening, and a lever connected to the deflector and to said stem.

FRANK L. MORSE.
